UNITED STATES PATENT OFFICE.

WILLIAM H. THIELL, OF CHICAGO, ILLINOIS.

PORTABLE BATH-ROOM AND WATER HEATER.

SPECIFICATION forming part of Letters Patent No. 607,791, dated July 19, 1898.

Application filed May 22, 1897. Serial No. 637,768. (No model.)

To all whom it may concern:

Be it known that I, WILLIAM H. THIELL, a citizen of the United States, residing at Chicago, in the county of Cook, State of Illinois, have invented a new and useful Improvement in Portable Bath-Room and Water Heaters, of which the following is a specification.

My invention is related to a class of water-heaters where gas is used for fuel through an ordinary hydrocarbon-burner; and the object of my improvement is to provide a water and room heater that can be easily conveyed from the kitchen-sink to the bath-room or wherever hot water is needed, and my device is so constructed as to be compact, small, and light. I attain these objects by a mechanism illustrated in the accompanying drawings, in which—

Figure 1 is a perspective view showing the heater. Fig. 2 is a top view with cover removed, showing the water-coil and top of gas-burners. Fig. 3 is a perpendicular sectional view cut on line 3 3, Fig. 2, showing a cross-section of the coil and the platform C drawn out from under the coil, with the gas-burners attached in position to be used as a room-heater.

Similar letters refer to similar parts throughout the several views.

The inclosing case A is made of any suitable metal, the front side being left open for the reception of the burners. It is provided with a removable hood B, open at top; a coil a, consisting of a flat tube made of very thin metal folded right and left, the folds being parallel with each other and connected at the ends by return-elbows, leaving small spaces between each lap. Said coil is set perpendicular to the plane of the case. The water-supply pipe f' f' is connected to the rear lap of the coil at the top edge b. The discharge-pipe h is connected to the front lap at the top edge h' and extends downward. The object of connecting the inlet and discharge pipes to the upper edge of the coil is to cause the coil to always retain water, thus preventing the coil from overheating before the water begins to circulate. The coil is then fitted in the case, resting on lugs a'. (Seen in Fig. 3.) The platform C is constructed of wood covered with metal and adapted to slide in between the end pieces k of the case, provided with a drawer-pull n. A series of six or more ordinary gas-burners d, connected to one supply-pipe D, are fixed to the platform, adapted

to slide under the coil when heating water, being held in place by a latch P. Two plain cocks e f are fixed to the two pipes, provided with levers g g', fixed to the handles. The levers are connected to each other by rod g². The object of thus connecting them is to enable the user to turn the water and gas on simultaneously. The connecting-rod g² has several holes provided at the end. The object of these holes is to regulate the flow of water. By moving the lever g to the outer hole g² one cock will be opened more than the other, thus supplying more gas and less water, or vice versa.

The method of using the heater when hot water is wanted is as follows: Convey it to the place where hot water is needed and connect the gas-jet on the wall with the gas-inlet on the heater with a hose-pipe and the hydrant with the water-inlet on the heater with a hose, have the discharge-pipe lead to the vessel or bath-tub, turn on the gas and water by opening the cocks, light the gas, and the water will flow out hot to the place desired. When used as a room-heater, unlatch the table, disconnect the two valves, and withdraw the gas-burners from underneath the coil, as seen in Fig. 3, and let the heat escape into the room.

I am aware that gas burned under a coil for the purpose of heating water is not new, and I do not claim it as a part of my invention; neither do I wish to confine myself to the specific form of coil, as it may be of any suitable shape; but

What I do claim, and wish to secure by Letters Patent, is—

The combination in a portable bath-room and water heater of a water-heating coil, of a supply-pipe therefor having a valve, the supply-pipe and discharge-pipe connected to the top edge of said coil, a gas-heater supported upon a slidable platform, the gas-supply for said heater being provided with a valve, a detachable connection between the water-supply valve and gas-supply valve whereby when it is desired to heat the apartment in which the water-heater is placed, the two valves may be disconnected and the gas-heater withdrawn for heating the room substantially as set forth.

WILLIAM H. THIELL.
